[57]

ABSTRACT

A jack for use in handling transmissions, the jack having a wheeled base, a lift arm swingably mounted on the base, there being means for raising and lowering the lift arm and a load-receiving head at the free end of the lift arm. A leveling assembly is carried by the jack and includes a link having one end thereof coupled with the load-receiving head and the other end thereof attached to the base whereby the head may be rotated about a transverse axis, the leveling assembly being operable by gear means carried by the jack and actuatable from either side thereof. The jack is powered by a hydraulic piston and cylinder assembly carried by the base of the jack, the piston having a guide member at the outer end thereof and seated within trackways on each side of the base.

TRANSMISSION JACK

It is the most important object of this invention to provide a jack for handling vehicle transmissions such as is normally done in service stations, automotive repair shops and the like, the jack being relatively simple in construction and operation whereby to greatly facilitate the handling of bulky and heavy vehicle transmissions as they are removed from or installed into the vehicles.

In order to accomplish this result there is provided a wheeled base having a lift arm pivotally coupled at one end thereof to the base, the other end of the lift arm having a load-receiving head thereon, there being a leveling assembly interconnecting the head and the base of the jack whereby the head may be rotated about a transverse axis and thus positioned with respect to the vehicle when the transmission is to be supported by the head.

It is a yet further aim of this invention to provide a transmission jack which is operated by a hydraulic power unit consisting of a piston and cylinder assembly coupled with a fluid reservoir, the piston having at its outer free end a transversely disposed guide member, which guide has rollers on each end thereof, the rollers being received in corresponding trackways on each side of the base whereby to minimize bending loads on the hydraulic cylinder. The fluid reservoir for the cylinder contains an anticavitation tube which precludes the unit from becoming air locked even though the pump which supplies fluid from the reservoir to the cylinder may be operated with the rear end of the jack elevated as is commonly done. Additionally, the pumping circuit of the hydraulic unit has a built-in release valve which protects the jack from overloading due to manual effort on the pump handle.

Yet another object of this invention is to provide a transmission jack having a base and a pair of legs extending therefrom, the legs being inclined outwardly with respect to the base whereby to present an open area beneath the head of the jack.

Other objects including significant details of construction will become apparent from the following specification and accompanying drawings, wherein:

FIG. 1 is a fragmentary top plan view of the transmission jack, parts being broken away to reveal details of construction;

FIG. 2 is a fragmentary, side elevational view of the transmission jack;

FIG. 3 is a fragmentary, sectional plan view of the leveling assembly; and

FIG. 4 is a fragmentary, partially sectional side elevational view of the transmission jack.

The transmission jack 10 includes, as its primary components, a wheeled base 12; a lift arm 14; a load-receiving head 16 at the normally outermost free end of the lift arms; a leveling assembly 18 coupled at one end with the base 12 and at the other end with the head 16; and means 20 for elevating the lift arm 14.

The base 12 includes a generally rectangular frame 22, which frame is made up of a pair of opposed side members 24 and 26, a cross member 28 at the normally forwardmost end of the frame 22, there being suitable additional transverse members carried rearwardly of member 28 to provide rigidity to the frame 22. At the rear end of the frame 22 a pair of laterally extending fenders 30 are provided, the fenders each carrying in depending relationship corresponding caster wheels 32 which serve to support the rear end of the jack 10.

A pair of legs 34 extend from the normally forward-most end of the frame 22 at a point substantially adjacent the cross member 28, the legs 34 each being inclined outwardly with respect to the frame 22 whereby to provide an open area 36 between the legs 34, beneath the forwardmost portion of lift arm 14 and beneath load-receiving head 16. Each of the legs 34 has a caster wheel 38 at the outermost end thereof and is also provided with a handle 40 extending longitudinally thereof, which handles 40 are usable, together with a handle 42, for moving or lifting the jack 10 in manners which cannot be accomplished through the utilization of caster wheels 32 and 38.

Thus, there is provided a wheeled base 12 which is capable of great portability due to the presence of the caster wheels 32 and 38 as well as the handles 40 and 42.

The lift arm 14 is pivoted to base extensions 44 which extend upwardly from the frame 22 as by a transversely extending pivot pin 46, said pin 46 extending through connecting plates 48 which are carried on each side of the lift arm 14 adjacent the rear end thereof whereby to permit swinging movement of the lift arm from a lowered position to a raised position.

Swinging movement of the lift arm 14 about pivot 46 is accomplished by virtue of a hydraulic drive unit which is powered by a suitable fluid such as oil for instance, said drive means 20 including a hydraulic cylinder and reservoir 50, the cylinder having a forwardly extending piston 52, the reservoir surrounding the cylinder and supplying fluid thereto upon manual actuation of a pump 53 by operating lever 54.

Cylinder 50 and piston 52 are within the confines of frame 22 and are in parallel relationship with the side members 24 and 26 of the frame. Said side members 24 and 26 each define a trackway 56 whereby there is presented a trackway on each side of the frame 22 in substantially parallel relationship to the piston 52. Each of the trackways, as best seen in FIG. 1 and 4, has an upper flange 58 and a lower rail 60, the same cooperating to define a channel 62 therebetween.

The free end of piston 52 carries a connector 64 extending transversely with respect to the piston 52, the connector 64 being secured to a guide 66 which is in turn coupled with trailing links 68. Guide 66 extends in parallel relationship to the connector 64 and spans the distance between the sides 24 and 26 of the frame 22. A roller 70 is carried at each end of the guide 66, the rollers each being received in corresponding trackways 56 and retained therewithin by means of spacers 72 which are carried by guide 66 between the trailing links 68 and the proximal rollers 70, all as is shown in FIG. 1 of the drawings.

When the hydraulic cylinder 50 is actuated by lever 54 and pump 53, the piston 52 is extended, raising arm 14, whereby the rollers 70 move along their corresponding trackways 56, rollers 70 being seated within channels 62 and retained at the outer end of piston 52 against twisting or bending by virtue of the loads imposed thereupon.

It will be appreciated that when the fluid is released from cylinder 50 as by actuating a release valve operation knob 74, the piston 52 is retracted under the urging of the supported load and supplemented by a pair of oppositely disposed return springs 76, said springs each having one end thereof hooked over guide 66 and the other end thereof connected to a corresponding lug 78 carried by the frame 22.

It is also notable that the fluid reservoir which serves the cylinder 50 contains an anticavitation tube which prevents air locking of the fluid delivery assembly when the pump 53 is actuated as by lever 54 even though the rear end of the jack may be in an elevated position as is common practice when handling certain types of transmissions. Furthermore, the pumping circuit has a pressure relief valve incorporated therewithin which protects the jack from overloading due to manual effort on the operating lever 54. Thus, while the jack will support an externally applied load on head 16, which load is much greater than the jack 10 will lift, the pressure relief valve serves as a safety feature preventing the elevation of a load which is heavier than the capacity thereof.

It will also be noted that the lifting capacity of the transmission jack 10 may be supplemented by additional jacks which may be utilized therewith when servicing the vehicle to support either the vehicle itself or components thereof adjacent the transmission of the vehicle, this being permitted by the open front area 36 which is defined by the outwardly spread legs 34, such open area, for instance, permitting a hand jack to be positioned therewithin and used to support the adjacent end of a vehicle engine while the transmission is removed.

To further assist in handling the transmission either as it is removed from the vehicle or replaced therewithin, the jack 10

is provided with previously mentioned leveling assembly 18. Assembly 18 is best shown in FIG. 3 of the drawing from which it is apparent that the same includes a link 80, said link being coupled at one end thereof with a mount 82 which carries the head 16 and at the other end thereof with a yoke 84 which is, in turn, coupled with a shaft 86.

The link 80 includes a pair of relatively shiftable, tubular members 88 and 90, the member 88 being coupled with a screw 92 through a collar 94 whereby, upon rotation of the screw 92, the member 88 is shifted telescopically with respect to the member 90. In order to accomplish rotation of the screw 92 and thus relative shifting movement of the members 88 and 90, there is provided a miter gear 96 on one end of the screw 92, which miter gear 96 meshes with a similar gear 98, which gear 98 is carried by rotatable shaft 86. The shaft 86 is suitably journaled within the sidewalls 24 and 26 of the frame 22 and is provided with cranks 100 at each end thereof whereby said shaft 86 may be rotated from either side of the transmission jack 10. The yoke 84 is likewise journaled for shifting movement with respect to the frame 22 whereby, upon rotation of the shaft 86 as by one of the cranks 100, the screw 92 will be rotated for instance in a right-hand direction thereby driving collar 94, which is secured to member 88, thereby causing member 88 to be shifted with respect to member 90. When this is done, and inasmuch as member 88 is coupled to mount 82 as by a pivot point 102, the mount will be rotated about a pivot rod 104 which connects lift arm 14 with the mount 82 in such a manner as to tilt the head 16 in a fore-and-aft direction with respect to the jack 10. Such tilting movement is accomplished by positioning the connection 102 at a point forwardly and downwardly of the pivot rod 104 whereby, as link 80 is extended and retracted, the attitude of the head 16 and, more particularly, a work-receiving platform 106 thereof will be rotated with respect to the horizontal.

It will be noted that the head 16 includes, in addition to platform 106, a plurality of outwardly extending arms 108 which are shiftable with respect to the platform whereby to be positionable with respect to the transmission when it is placed upon the platform 106, thereby supporting and gripping the transmission and permitting chains 110 to be securely wrapped about the transmission to thereby preclude any subsequent shifting movement thereof on the platform 106. It is also notable that there is a centrally disposed bolt 112 which permits rotation of the platform 106 about a vertical axis. Also, an operating knob 114 is provided and coupled with suitable structure (not shown) whereby side-to-side tilting movement of platform 106 may be accomplished.

Thus, through utilization of the jack hereinabove described, the same may be positioned beneath a vehicle to receive the transmission thereof as it is removed, the platform 106 upon which the transmission is to rest being shiftable in several directions as by leveling assembly 18; vertical axis 112; and operating knob 114, all to the end that the platform 106 may be adjusted to the most advantageous position for handling the transmission. By the same token, when the transmission is to be replaced, the several various adjusting features may be utilized, in cooperation with the lift arm 14, to place the transmission in the exact desired position to permit replacement thereof.

It will be readily appreciated that the head 16, as shown for purposes of illustration in this disclosure, may be replaced by other types of load-receiving heads which would function equally well with the transmission jack 10 hereinabove described.

It is also notable that, when the lift arm 14 moves from a raised to a lowered position, there is suitable clearance between the edges of the lift arm and the sides 24 and 26 of the frame 22 so that the fingers or the hands of the user of the jack will not be caught or pinched between the lift arm and the frame.

Having thus described the invention, what is claimed as new and desired to be secured by letters patent is:

1. A transmission jack comprising:
a base;

a lift arm swingably mounted on said base;
means for swinging said lift arm between lowered and raised positions;
a load-receiving head carried at one end of said lift arm, the other end of the arm being pivotally connected to the base;

means for rotating said head with respect to said arm, said means including a mount for said head, said mount being rotatable about a transverse axis, said mount being connected to said one end of the lift arm by a horizontally disposed pivot pin, said pin defining said transverse axis and a link coupling the mount with the base, said link having one end thereof attached to said mount at a position located normally forwardly and downwardly with respect to said pivot pin, the other end of the link being coupled with said base; and
operating controls for said last mentioned means located on both sides of said base.

2. A transmission jack as set forth in claim 1, said head being rotatable about a vertical axis with respect to said mount.

3. A transmission jack comprising:

a base;
a lift arm swingably mounted on said base;
means for swinging said lift arm between lowered and raised positions;
a load-receiving head carried at one end of said lift arm, the other end of the arm being pivotally connected to the base;

means for rotating said head with respect to said arm, said rotating means including a mount for said head, the mount being rotatable about a transverse axis, said mount being connected to said one end of the lift arm by a horizontally disposed pivot pin, said pin defining said transverse axis and a link coupling said mount with said base, the link including a pair of relatively shiftable members whereby said link is longitudinally extensible and retractable;

screw means coupled with one of said members for shifting said member with respect to the other member;
gear means coupled with said screw means for rotating the latter and thereby shifting said member, said gear means being carried by said base, there being a control crank on at least one side of said base for driving said gear means whereby to effect rotation of said head about a transverse axis through said link; and
operating controls for said rotating means located on at least one side of said base.

4. A transmission jack comprising:
a base;
a lift arm swingably mounted on said base;
means for swinging said lift arm between lowered and raised positions, said means for swinging the lift arm including a hydraulic piston and cylinder assembly coupled with said arm, said assembly being carried by the base, the base including a frame, said frame having a pair of opposed trackways in spaced relationship to the piston of said assembly, and a guide carried by the free end of the piston in perpendicular relationship thereto, said guide having the ends thereof received in corresponding trackways;

a load-receiving head carried at one end of said lift arm, the other end of the arm being pivotally connected to the base;
means for rotating said head with respect to said arm; and
operating controls for said last mentioned means located on both sides of said base.

5. A transmission jack as set forth in claim 4, there being rollers on the ends of said guide, the rollers being received by corresponding trackways.

6. A transmission jack as set forth in claim 5, there being return springs interconnecting said guide and said base.

7. A transmission jack as set forth in claim 6, said base including a pair of legs extending from said frame and inclined outwardly with respect thereto whereby to define an open front area beneath said head.
